UNITED STATES PATENT OFFICE.

WILLIAM S. BECHTOLD, OF NEWARK, NEW JERSEY.

DESIGN FOR A BARRETTE OR COMB.

• 41,122.

Specification for Design.

Patented Jan. 24, 1911.

Application filed September 30, 1910. Serial No. 584,770. Term of patent 3½ years.

To all whom it may concern:

Be it known that I, WILLIAM S. BECHTOLD, a citizen of the United States, residing at Newark, in the county of Essex and State of New Jersey, have invented a new, original, and ornamental Design for Barrettes or Combs, of which the following is a specification, reference being had to the accompanying drawing, forming part thereof.

The figure is a plan view of a barrette or comb, showing my new design.

I claim:

The ornamental design for a barrette or comb, as shown.

WILLIAM S. BECHTOLD.

Witnesses:

CHARLES J. KIERAN,
A. P. LAMBRECHT.
